UNITED STATES PATENT OFFICE.

MARK JAY SAMUELS, OF NEW YORK, N. Y., ASSIGNOR TO LYRAPHONE COMPANY OF AMERICA, OF WASHINGTON, DISTRICT OF COLUMBIA, A CORPORATION OF DELAWARE.

DESIGN FOR A TALKING-MACHINE CASE.

48,397.

Specification for Design.

Patented Jan. 4, 1916.

Application filed October 27, 1915. Serial No. 58,289. Term of patent 7 years.

To all whom it may concern:

Be it known that I, **MARK J. SAMUELS**, a citizen of the United States, and a resident of the borough of Manhattan, city, county, and State of New York, have invented a new, original, and ornamental Design for Talking-Machine Cases, of which the following is a specification, reference being had to the accompanying drawing, forming a part thereof.

Figure 1 is a front elevation of a talking machine case, showing my design, and Fig. 2 is a plan view thereof.

Copies of this patent may be obtained for five cents each, by addressing the "Commissioner of Patents, Washington, D. C."

I claim:

The ornamental design for a talking machine case, as shown.

In testimony whereof I have signed this specification in the presence of two subscribing witnesses.

MARK JAY SAMUELS.
